US0D1023349S

(12) **United States Design Patent** (10) Patent No.: **US D1,023,349 S**
(45) Date of Patent: ** Apr. 16, 2024

(54) **SLAB COMPRISING PARTICULATE MINERAL MIXTURE**

(71) Applicant: **Cambrria Company LLC**, Eden Prairie, MN (US)

(72) Inventors: **Jon Louis Grzeskowiak, II**, Prior Lake, MN (US); **Summer Lane Kath**, Eden Prairie, MN (US); **Martin E. Davis**, Excelsior, MN (US)

(73) Assignee: **Cambrria Company LLC**, Eden Prairie, MN (US)

(**) Term: **15 Years**

(21) Appl. No.: **29/783,492**

(22) Filed: **May 13, 2021**

(57) **CLAIM**

The ornamental design for a slab comprising particulate mineral mixture, as shown and described.

DESCRIPTION

The file of this patent contains at least one drawing/photograph executed in color. Copies of this patent with color drawing(s)/photograph(s) will be provided by the Office upon request.

The sole FIGURE is a top plan view of a slab comprising particulate mineral mixture, showing our new design. The depicted surface of the slab comprising particulate mineral mixture is flat.
